UNITED STATES PATENT OFFICE.

HENRY HAVELL, OF NEWARK, NEW JERSEY.

IMPROVEMENT IN THE MODE OF ATTACHING THE EYES TO THE BLADES OF HOES.

Specification forming part of Letters Patent No. **16,584**, dated February 10, 1857.

To all whom it may concern:

Be it known that I, HENRY HAVELL, of the city of Newark, in the county of Essex and State of New Jersey, have invented a new and useful Improvement in the Mode of Attaching Malleable-Iron Eyes to Hoes; and I do hereby declare the following to be a full, clear, and exact description of the same, reference being had to the accompanying drawings, which drawings are lettered to correspond with and constitute a part of this specification.

In order that the public may fully understand the nature of my invention and those skilled in the art be enabled to construct the same, I will describe it as follows:

Figure 1 is a perspective view of a hoe having a malleable-iron eye attached to it after my plan. Fig. 2 is a representation of the wrought-iron cap A and the steel blade B, ready to receive the pad of the eye. This wrought-iron cap, or its equivalent, is made to correspond with the shape of the malleable-iron pad or lower projection of the eye C, Fig. 3, and is sufficiently raised in the center to allow the pad of the eye to pass into the socket formed by the flat surface of the blade B and the wrought-iron cap A.

When each of the separate parts are in their proper places the whole is heated to the re-

quired heat for welding and then placed under a drop-hammer, that completes the operation of attaching the eye by a single blow in such a manner that any sudden stroke upon the back of the blade will not loosen the eye, as is the case with most of the hoes that have cast-iron eyes simply welded upon the blade without being protected by a cap, or otherwise secured to the blade. The wrought-iron cap adheres to both the steel blade and malleable-iron pad of the eye, consequently when welded forms a part of the whole and makes a stronger and better finish.

I do not claim the individual parts of a hoe, neither do I claim welding the malleable-iron eye to the blade; but

What I claim, and desire to secure by Letters Patent of the United States, is

The cap A, which forms a socket with the blade B to receive the malleable-iron eye, and becomes a part of the same, in the manner and for the purpose substantially as described.

In testimony whereof I hereunto subscribe my name in the presence of two witnesses.

HENRY HAVELL.
